US0D1033350S

(12) **United States Design Patent** (10) **Patent No.:** **US D1,033,350 S**
(45) **Date of Patent:** **** Jul. 2, 2024**

(54) **CASE WITH EARPHONES**

- (71) Applicant: **Apple Inc.**, Cupertino, CA (US)
- (72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Daniel J. Coster**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Joe Sung-Ho Tan**, Vienna (AT); **Clement Tissandier**, San Francisco, CA (US); **Eugene Antony Whang**, San Francisco, CA (US); **Rico Zörkendörfer**, San Francisco, CA (US)

- (73) Assignee: **Apple Inc.**, Cupertino, CA (US)

- (**) Term: **15 Years**

- (21) Appl. No.: **29/886,778**

- (22) Filed: **Mar. 13, 2023**

Related U.S. Application Data

- (63) Continuation of application No. 29/849,506, filed on Aug. 11, 2022, now Pat. No. Des. 980,629, which is

a continuation of application No. 29/752,516, filed on Sep. 28, 2020, now Pat. No. Des. 960,829, which is a continuation of application No. 29/726,068, filed on Feb. 28, 2020, now Pat. No. Des. 897,291, which is a continuation of application No. 29/692,476, filed on May 24, 2019, now Pat. No. Des. 878,045, which is a continuation of application No. 29/594,338, filed on Feb. 17, 2017, now Pat. No. Des. 849,401, which is a continuation of application No. 29/576,707, filed on Sep. 6, 2016, now Pat. No. Des. 806,388.

(57) CLAIM

The ornamental design for a case with earphones, as shown and described.

DESCRIPTION

FIG. 1 is a top front perspective view of a case with earphones showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the case with earphones that form no part of the claimed design.
